UNITED STATES PATENT OFFICE.

HARRY F. WOERNLEY, OF ALLEGHENY, PENNSYLVANIA, ASSIGNOR TO THE WESTINGHOUSE AIR BRAKE COMPANY, OF PITTSBURG, PENNSYLVANIA, A CORPORATION OF PENNSYLVANIA.

DRAW-GEAR AND BUFFING APPARATUS.

SPECIFICATION forming part of Letters Patent No. 775,959, dated November 29, 1904.

Application filed March 13, 1902. Serial No. 98,019. (No model.)

To all whom it may concern:

Be it known that I, HARRY F. WOERNLEY, a citizen of the United States, residing in Allegheny, county of Allegheny, State of Pennsylvania, have invented or discovered a certain new and useful Improvement in Draw-Gear and Buffing Apparatus, of which improvement the following is a specification.

My invention relates to draw-gear and buffing apparatus for cars, and has for its object to provide a construction by which a single yielding draft and buffing mechanism may be utilized to take up the shocks and resist both the draft and buffing strains from either or both ends of the car.

My invention is adapted to be employed in connection with an ordinary draft and buffing spring or with any preferred type of spring or friction draft and buffing mechanism; and it consists in providing intermediate connections between the draw-bars or couplings at each end of the car and the yielding resistance mechanism, by means of which connections the draft and buffing strains from either end of the car are transmitted to the said yielding resistance member.

The invention also comprises an improved and novel form of connection adapted to transmit the strains from either end of the car axially to the resistance mechanism.

The invention further consists in other improved constructions and novel combinations, all as hereinafter more fully set forth.

In the accompanying drawings, Figure 1 is an inverted plan view of my improved apparatus applied to the frame of a car; a part thereof being broken away. Fig. 2 is a side elevation. Fig. 3 is a transverse section taken on the line $x-x$ of Fig. 1. Fig. 4 is a transverse section taken on the line $y-y$ of Fig. 1, and Fig. 5 is a detail view showing two elevations of my improved follower-plate.

According to my invention the spring or friction draft and buffing mechanism which is employed to take up the strains is preferably located beneath the center of the car, and for this purpose I provide a large casting 1, adapted to be secured by bolts to the center draft-

timbers 2 and 3 of the framework of the car. The casting is formed with cored passages and 50 ribs to give the proper lightness and strength, two pairs of draft-lugs or abutments 4, and flanges for suitably guiding the follower-plates 5. Any other desirable means may be used for connecting the draw-gear to the framing of the car. The follower-plates 5 normally bear against the lugs or abutments 4, and between the follower-plates is located the yielding draft and buffing mechanism 6, which may be of any ordinary or preferred design, that 55 indicated in the drawings being a friction draft and buffing mechanism, such as shown in Patent No. 629,943, issued to George Westinghouse August 1, 1899. At each end of the car the draw-head 11 is pivotally 60 connected to the draw-bar 9, which at its inner end is provided with a buffing-block 7, adapted to bear against the outer side of the follower-plate 5. In the end of the block 7 is formed the recess or slot 8, into which extends the flange or rib 13 on the back of the follower-plate. A strap 12 is secured to each block 7 and passes around both the follower-plates 5 and the friction draft and buffing mechanism and through the slot 8 of the opposite block, engaging therein the flange 13 of the follower-plate. Guide-pieces 10 may be used for supporting and guiding the draw-bars 9, and the straps 12 may be supported and guided by means of the bent plate 14, 65 bolted to the lugs 4 of the casting 1, or by any other suitable means. It will be noticed that the corresponding parts on both sides of the center are duplicates and interchangeable. Each strap 12, with its corresponding slot 8 70 and flange 13, is located in a plane which is inclined to the vertical; but the planes are inclined in opposite directions, so that each strap passes through the loop of the other and the planes intersect on a horizontal line 75 which coincides with the axis of the friction draft and buffing mechanism. By this means all draft and buffing strains from either end of the car will be transmitted axially to the said friction-resistance mechanism. 80

The operation of the device is the same

- from either end of the car, the draft-strains being transmitted through the draw-bar 9 and strap 12 to one of the follower-plates, while the other follower-plate is held stationary 5 against the corresponding lugs 4 of the casting, and the resistance-spring and friction mechanism 6 is compressed between said follower-plates. In buffering the action is similar, except that the strain is transmitted through 10 the block 7 directly to one of the follower-plates, while the other follower-plate engages the stop-lugs or abutments 4, the slots 8 being long enough to allow a sufficient free movement of the ends of the straps.
- 15 Heretofore it has been the practice to employ two sets of draft and buffering mechanism on a car, one set being placed at each end; but by means of my improved connections a single mechanism of this type may be utilized 20 to take up the shocks and resist the strains due to draft and buffering from either or both ends of the car, thus saving great expense in the equipment.
- Having now described my invention, what 25 I claim as new, and desire to secure by Letters Patent, is—
1. In a draw-gear and buffering apparatus, the combination with the draw-heads and a yielding draft and buffering mechanism for transmitting stresses to the car-frame, of intermediate independent connections adapted to transmit the draft and buffering strains from either end of the car to said draft and buffering mechanism.
  - 30 2. In a draw-gear and buffering apparatus for cars, the combination with a draw-head at each end of the car and a yielding resistance mechanism for transmitting stresses to the car-frame, of independent means connecting each draw-head with the yielding resistance mechanism and adapted to transmit draft and buffering strains from either end of the car axially to said mechanism.
  - 35 3. In a draw-gear and buffering apparatus, the combination with a yielding resistance mechanism and follower-plates for transmitting stresses to the car-frame, of a draw-bar at each end of the car and an independent connection from each draw-bar engaging one of the follower-plates.
  - 40 4. The combination on a car, of a yielding resistance member, follower-plates therefor, a draw-bar at each end of the car and a strap

secured to each draw-bar and passing around the follower-plates.

55

5. In a draw-gear, the combination with a draw-bar at each end of the car and a yielding resistance mechanism for transmitting stresses to the car-frame, of independent means connecting each draw-bar with the yielding resistance mechanism and adapted to transmit draft strains from either draw-bar to said mechanism.

6c

6. In a draw-gear, the combination of a yielding resistance member, a draw-bar at each end of the car, and a strap secured to each draw-bar, each strap passing through the other and around the yielding resistance member.

7. In a draw-gear, the combination of a yielding resistance member, a draw-bar at each 70 end of the car, and a strap secured to each draw-bar and passing around the yielding resistance member, the plane of each strap being inclined to the vertical.

8. In a draw-gear, the combination with a 75 draw-bar at each end of the car, a yielding resistance mechanism and follower-plates therefor, of slotted buffering-blocks connected to the draw-bars for engaging the follower-plates, and a strap secured to each draw-bar and extending into the slot of the opposite buffering-block.

80

9. In a draw-gear, the combination with a draw-bar at each end of the car, a yielding resistance mechanism, and means for transmitting the draft and buffering stresses from the yielding resistance mechanism to the car-frame, of independent means connecting each draw-bar with the yielding resistance mechanism and adapted to transmit stresses from 90 either draw-bar to said mechanism.

85

10. In a draw-gear, the combination with abutments secured to the car-frame, follower-plates engaging said abutments, and a yielding resistance mechanism located between the 95 follower-plates, of a draw-bar at each end of the car, and independent means connecting each draw-bar with the yielding resistance mechanism and adapted to transmit stresses from either draw-bar to said mechanism.

95

In testimony whereof I have hereunto set my hand.

HARRY F. WOERNLEY.
